US0D1048420S

(12) **United States Design Patent** (10) **Patent No.:** **US D1,048,420 S**
(45) **Date of Patent:** **** Oct. 22, 2024**

(54) **POSTURE CORRECTION DEVICE**

(71) Applicant: **Deyi Sun**, Tianjin (CN)

(72) Inventor: **Deyi Sun**, Tianjin (CN)

(**) Term: **15 Years**

(21) Appl. No.: **35/519,920**

(22) Filed: **Jan. 11, 2024**

(80) **Hague Agreement Data**

Int. Filing Date: **Jan. 11, 2024**

Int. Reg. No.: **DM/234671**

Int. Reg. Date: **Jan. 11, 2024**

Int. Reg. Pub. Date: **Feb. 2, 2024**
